BALL PAINTING MACHINE

Frederick T. Driscoll, Cloyd D. Smith, and Stanley
Morris Briggs, Los Angeles, Calif., assignors to
Ball Re-Nu, Inc., a corporation of California

Application May 24, 1947, Serial No. 750,194

10 Claims. (Cl. 91—46)

1

This invention relates to a machine for coating balls. It is particularly applicable to the coating of golf balls and has as one of its objects to provide a coin controlled golf ball painting machine which may be installed at the club house or at any convenient location at a golf course, making it possible for all golfers using the course to have their balls freshly repainted at the course.

The invention is, however, broadly applicable to other species of ball painting machines, such as, for example, continuously operable machines for the industrial painting of balls of various kinds.

In its broader aspect, the invention contemplates a machine embodying mechanism for automatically picking up a ball while moving uninterruptedly in a predetermined path, subjecting the ball to a painting operation at a point in said path removed from the pickup point, subjecting the ball to a drying operation during a further stage of movement along said path, and discharging the ball at a further point along said path.

One of the objects of the invention is to provide for completing the cycle of operations with a minimum wastage of the time period consumed in completing the movement of the ball through the predetermined path. To this end, the invention, in one of its more specific aspects, contemplates movement of the ball in a circular orbit, with the pickup and discharge points located at closely adjacent points on such path, whereby the pickup may occur at the beginning of the orbit and the discharge at the end of the orbit.

Another object of the invention is to provide novel means for supporting the ball at the pickup point and for automatically picking up the ball and withdrawing it from such supporting means.

A further object is to provide a compact arrangement of the several mechanisms for operating upon the ball. It is preferred to employ an immersion bath for the painting operation. This requires the use of a tank for holding the paint, and in order to provide for the movement of the ball into and out of such tank in a circular path, the circular path is arranged in a vertical plane, and the tank is placed at the lower extremity of the circular path. The pickup point is arranged at one side of the path, and the drying mechanism commences at the other side of the path and occupies a major portion of the upper half of the path, whereby the ball is subjected to a drying operation for a maximum period of time and right up to the point of discharge.

2

A further object of the invention is to provide means for supporting the ball in such a manner that the entire surface of the ball may be coated by immersion. This is accomplished by employing a pair of needle-pointed jaws adapted to grasp the ball at diametrically opposed points, such jaws being carried by a pair of inwardly constraining spring arms which are forced apart by suitable means disposed in the path of movement thereof, just prior to the time the ball supporting mechanism reaches the pickup point. The ball is supported by a yieldable fork. As the ball carrying means reaches the center of the ball, the spreading means releases the yieldable arms and permits the pointed jaws to engage the ball. The continued movement of the ball carrying means is then applied to the ball, and the yieldable supporting means is pushed back out of the way as the ball is removed therefrom.

Coating by immersion involves a number of problems. It coats the ball with a continuous film of paint which is more difficult to dry and harden than would be, for example, a sprayed coating. A rapidly drying paint, preferably of a lacquer type, must therefore be employed. But this creates the problem of avoiding the formation of a film or scum on the body of paint in the tank. Toward the solution of this problem, the invention has, as a further object, to provide mechanism for normally maintaining the paint tank covered, automatically uncovering the tank during that portion of a cycle of operation in which the ball is being carried through the tank, and then re-covering the tank as soon as the ball has been removed from the tank.

As another means for handling this problem, the invention provides a novel and improved arrangement of tank and agitating mechanism, such as to produce maximum agitation and without unduly enlarging the space within the tank to accommodate such agitating mechanism.

Another problem arising from the use of an immersion coating method, is that of avoiding the formation of a tear on the ball from excess paint adhering thereto. We have discovered that this problem can be successfully met by rotating the ball during the drying operation, and accordingly, a further object of the invention is to provide a ball coating machine having means for producing rotation of the ball carrying means during at least the initial portion of the drying stage.

One of the major problems in the development of a "paint-while-you-wait" machine is the problem of drying the ball in a minimum period of

time. One of the primary requisites of such a machine is the reduction to a minimum of the period of time that the golfer must wait to receive the painted ball. Accordingly, a further object of the invention is to provide drying mechanism that will act rapidly and efficiently to dry and harden the paint coating sufficiently so that when the ball is discharged, the coating will be substantially hard and tough. We have found that satisfactory results can be secured by employing a battery of infra-red lamps, arranged adjacent the path of movement of the ball, together with a means for discharging a stream of drying air upon the ball or for circulating air around the ball as it is being dried.

A further object of the invention is to provide means for automatically releasing the ball from the ball carrying jaws at the delivery point.

Another object is to provide means for correlating the ball rotating means with the ball releasing means so that the latter may operate properly.

Another object is to provide control means for automatically initiating and stopping the operation of the various units of the machine at the proper stages in the cycle of operation.

Another object is to provide a machine which combines all of the foregoing characteristics in a structure that is reasonably simple, certain in its operation, not easily thrown out of order, and sufficiently inexpensive in construction, operation and upkeep.

Other objects will become apparent in the ensuing specification and appended drawings in which:

Fig. 1 is a perspective view of a golf ball painting machine embodying our invention;

Fig. 2 is a vertical sectional view of the same taken on the line 2—2 of Fig. 1;

Fig. 3 is a detail of the cam for controlling the operation of the drying mechanism;

Fig. 4 is a detail of the cam for controlling the operation of the tank covering mechanism;

Fig. 5 is a transverse sectional view of the machine taken on the line 5—5 of Fig. 2;

Fig. 6 is a horizontal sectional view of the machine taken on the line 6—6 of Fig. 2;

Fig. 7 is a front view of the machine, the cover thereof being shown in section and in an open position;

Fig. 8 is a detail sectional view of the ball rotating mechanism;

Fig. 9 is another sectional view of the ball rotating mechanism;

Fig. 10 is a transverse sectional view of the ball rotating mechanism;

Fig. 11 is a sectional view of the pickup portion of the machine;

Fig. 12 is a sectional view of the paint tank portion of the machine;

Fig. 13 is a detail of that portion of the machine which contains the battery of infra-red lamps and the rotating mechanism;

Fig. 14 is a detail sectional view of the delivery portion of the machine;

Fig. 15 is a detail of the pickup mechanism;

Fig. 16 is a wiring diagram of the operating controls of the machine;

Fig. 17 is a schematic view of a modified form of the invention, suitable for use in a ball manufacturing plant, for the initial painting of new balls in quantity; and

Fig. 18 is a detail of the ball feed mechanism of Fig. 17.

As an example of one form in which our invention may be embodied, we have shown in Figs. 1 to 15, inclusive, a coin controlled ball painting machine embodying a casing 21, a door 22 hinged to the casing 21 as at 23 (Fig. 7), a suitable lock and handle unit 24 for manipulating the door 22, a coin receiving unit 25 having a coin slot 26 and preferably embodying suitable coin selector mechanism of any known type for rejecting slugs, etc., a ball inlet 27, a ball outlet 28, and internal operating mechanism which will shortly be described. The inlet 27 and outlet 28 are preferably arranged closely adjacent each other and may be embodied in a unitary fitting 29. Also, they are preferably arranged adjacent the coin box 25. The operating mechanism includes:

General arrangement of operating mechanism

The ball 39 that is to be painted is carried in a circular path or orbit (which is indicated in Fig. 7 at 31) by ball carrying means which is indicated generally at A and is mounted upon a shaft 37 for rotation about the axis of the orbit 31.

The various units which operate directly upon the ball are arranged adjacent the orbit 31. The casing 21 is shaped to accommodate the circular shape of the orbit 31 and therefore preferably includes a semi-cylindrical dome portion 32. Below the dome portion 32, the casing is preferably rectangular, including vertical side walls 33, a rear wall 34, and a shelf 35 bridging between the side walls 33.

The carrying mechanism A picks up the ball and removes it from the ball supporting and pick-up controlling unit B which is located at one side of the orbit 31, preferably at a point substantially horizontally opposite the shaft 37. From the pick-up point, the ball is carried downwardly as indicated by the arrow 38 and is passed through the coating tank unit which is indicated generally at C. After passing through the coating tank, the ball is carried upwardly past a battery of infra-red lamps, indicated generally at D, and thence past a blowing or air circulating unit which is indicated generally at D', the units D and D' collectively constituting the drying mechanism. The ball is thence delivered to the ball discharging unit E.

Ball carrying mechanism

The ball carrying mechanism A includes an arm 41 which is secured at one end to the forward end of the shaft 37. For each cycle of operation of the machine, the arm 41 is moved by the shaft 37 through 360° of arcuate movement about the axis of the shaft 37. Such movement is initiated by the dropping of a coin in the slot 26 and is carried out by an electric motor 42, energized by the closing of a coin operated switch 43 (see Fig. 16) and energized only when the full 360° of rotation has been completed.

The motor 42 drives the shaft 37 through gearing, including a worm 44 on the motor shaft, driving a worm wheel 45 on a shaft 46 which carries a worm 47 driving a worm wheel 48 on the shaft 37. Such gearing is preferably encased in gear housing means 49 which may be mounted, as at 50, upon a horizontal bracket member 51 secured to the rear casing wall 34. Any suitable reduction gearing for providing a reduced drive from an electric motor to the shaft 37 may be employed, and the particular arrangement above described is merely illustrative.

The ball rotating means includes a tubular stub shaft 52 rotatably mounted on the arm 41 (Figs. 7, 8 and 9). Rotatable connection is provided by

a bushing 53 secured in the stub shaft 52 and journaled upon a bolt 54 which is mounted in a sleeve 55 secured in the end of the arm 41, which is likewise tubular. A star wheel 56 is secured to the end of the bushing 53. The star wheel 56 has teeth that are adapted to mesh in openings 57 (Figs. 10 and 7) in a rack plate 58. The rack plate 58 is supported in a vertical plane just rearwardly of the plane of rotation of the arm 41, upon any suitable bracket means such as the horizontal bracket members 51 and 59, and a vertical bracket member 60 which may all be secured to the rear wall 34, with the member 60 bridging between the members 59 and 51 as indicated in Fig. 7. The openings 57 are arranged in an arc concentric to the axis of the shaft 37, and the rack plate 58 terminates just beyond the openings 57 in a peripheral edge which is correspondingly concentric. This permits the ball engaging fingers, which will now be described, to rotate freely beyond the periphery of the plate 58.

Secured to the outer end of the stub shaft 52 are a pair of spring fingers 61. The fingers 61 (Figs. 5 and 13) have diverging portions 62 and parallel portions 63 extending from the ends of the diverging portions 62. Mounted in the parallel portions 63 and extending toward each other, in axial alignment, are a pair of needle-pointed ball engaging jaws 64.

The spring fingers 61 are normally disposed in a plane transverse to the plane of rotation of the arm 41. This position of the fingers 61 is determined by the engagement of a pair of wedge shaped lugs 65 secured to the face of the star wheel 56 (Fig. 9) in a pair of V-shaped notches 66 in the outer end of the sleeve 55. The lugs 65 are yieldingly maintained in the notches 66 by a coil spring 67 engaged under compression between the inner end of the sleeve 55 and a head 68 on the bolt 54. When the star wheel 56 engages the rack plate 58, the stub shaft 52 will be forced to rotate, and the lugs 65 will be forced out of the notches 66 by cam action and will ride past the notches as the shaft 52 rotates.

Pickup mechanism

The pickup unit B (Figs. 2, 5, 7 and 15) includes a short chute 71 having an inlet registering with the inlet 27 of the fitting 28. The chute 71 may comprise a pair of vertical side walls 72 (Figs. 11 and 15) having at their upper extremities flanges 73 secured to a horizontal bracket member 74, and having converging lower portions 75 terminating in downwardly extending flanges 76. A retractable ball support 77 (Figs. 7 and 11) has at one end a hinge eye 78 by which it is hinged upon a hinge pin 79 mounted in the ears 76. The pin 79 may have the additional function of tying the ears 76 together to maintain the proper spacing between the converging portions 75, which constitute the rollway for the ball 36. The retractable ball support 77 terminates in an upwardly curved finger 80 against which the ball 36 comes to rest after having rolled through the chute 71. The support 77 also has a pair of lateral upwardly curved fingers 81 (Figs. 2 and 7) which cooperate with the finger 80 to form a basket-like support for the ball 36 beyond the end of the chute 71. In order to avoid any possibility of a ball jumping over the finger 80, after having rolled down the chute 71, we may also provide a guard finger 82 projecting downwardly from the bracket member 74.

It may now be noticed that the ball is brought

to rest in a pickup position (shown in Fig. 7) beyond the end of the chute 71, in order that it may be engaged by the needle-pointed jaws 64 of the ball carrying mechanism. The jaws 64 move in a path which clears the inner end of the chute 71. The parallel end portions 63 of the fingers 61, however, project beyond the end of the chute 71 so as to engage cams 83 which project laterally from the end of the chute. The cams 83 (Fig. 5) are formed as flanges on the ends of the side wall portions 72 of the chute 71. The camming edges of these flanges (Fig. 11) include downwardly diverging rising portions 84, which spread the finger portions 63 as they ride downwardly thereover, until the points of the jaws 64 clear the side extremities of the ball 36. The lower ends of the cams 83 drop off sharply as at 85 to allow the jaws 64 to come together and engage the ball 36 just as their common axis intersects the center of the ball.

With the jaws in engagement with the ball, the spring fingers 61 are still spread apart under sufficient spring bias to cause the jaws to securely grip the ball between them. This grip is sufficient to transmit the movement of the ball carrying unit A through the ball to the retractable support 77, causing the support to be pushed downwardly (as shown in Fig. 11) and outwardly beyond the path of movement of the ball, until the ball is removed from the retractable support. This downward movement of the retractable support is resisted yieldingly by a coil spring 86 (Figs. 7 and 15) one end of which is attached to the bracket member 74 and the other end of which is attached to an arm 87 projecting from one side of the retractable support 77. The arm 87 engages a shoulder 88 at the lower edge of the inner end portion of one of the rollways 75, projecting beyond the hinge pin 79. This forms a stop to limit the upward movement of the retractable support 77 under the pull of the spring 86 so as to accurately position the support 77 for supporting the ball 36 in the pickup position. The entire support 77 including the body portion thereof, the eye 78, the fingers 80 and 81 and the arm 87, may be formed as a simple stamping.

Coating tank

The tank C includes front and rear walls 91 and 92 and a bottom 93 joined to the walls 91 and 92 to form a V-shaped trough 94. The upper region of the trough 94 provides a space approximating in shape the sweep of the ball path 31. The remainder of the trough, below the path 31, accommodates an agitator comprising a shaft 95 and a vane 96 secured thereto. The tank is just wide enough from front to rear to receive the spring fingers 61 of the ball carrying mechanism, in the normal transverse position of said fingers, and gives ample clearance between the walls 91 and 92 and the portions 63 of the fingers. A body of paint 97 is maintained in the trough 94 at a sufficient height to provide for complete immersion of the ball for a substantial period of arcuate movement thereof.

Since the use of a rapidly drying paint is contemplated, it is necessary, to avoid undue oxidation of the surface of the paint body, to maintain the tank C covered at all times except during the stage of movement of the ball through the tank. We therefore provide a cover 98 hinged at 99 to the rear wall 92 of the tank and adapted to be raised to an upstanding position as shown in dotted lines in Fig. 2.

The raising of the cover 98 is provided for by a cable 100, wound around a drum 101, attached at one end to a semi-circular drum segment 102 that is secured, as at 103, to the cover 98, with its periphery concentric with the hinge 99, and attached at its other end to a spring 103 which is anchored to the shelf 35 by any suitable means, such as the bracket 124. The spring 103 maintains the cable 100 yieldingly in frictional engagement with the drum 101.

The drum 101 is secured to an end portion of a shaft 104 which is rotatably and slidably journaled in a bearing 105 secured to the shelf 35. The shaft 104 is in axial alignment with the shaft 95, which projects through a bearing 106 in the rear wall 92 of the tank and has secured to its rear end a pulley 107 that faces the drum 101 and is normally slightly spaced therefrom. The shaft 95 is driven from an electric motor 109 through a pulley 110 and a belt 111 traveling on the pulley 110 and the pulley 107. Drive is transferred to the drum 101 by shifting the same into face to face clutching engagement with the drive pulley 107. This is provided for by a shift lever 112 which engages the rear end of the shaft 104. One end of the lever is pivoted, at 113, to a bracket 114 attached to the rear housing wall 34, and the other end of the lever is acted upon by a solenoid 115 through the medium of a shaft 116 attached to the solenoid armature 117, and an over-travel spring 118 interposed between the lever 112 and a head 119 on the end of the shaft 116. The shaft 116 passes freely through an opening 120 in the lever 112. Spring 118 is adapted to be compressed to permit the necessary over-travel of the solenoid armature in its normal operation.

The shifting movement of the shaft 104 is resisted by a coil spring 121 which encircles the shaft 104 and is engaged under compression between the bearing 105 and a collar 122 secured to the end of the shaft 104. The coil spring 121 normally maintains the drum 101 with its hub abutted against the bearing 105, slightly spaced from the pulley 107 as shown in Figs. 2 and 6.

When the drum 101 is engaged with the pulley 107, it will receive rotation therefrom and transmit a pull to the cable 100 to raise the cover 98 to the upstanding position shown in dotted lines in Fig. 2. It will be stopped in this position by engagement of the drum segment 102 with the rear tank wall 92, and the pulley 107 will then slip with reference to the drum 101, or the drum 101 will slip with reference to cable 100, maintaining the cover 98 in the raised position until the drum 101 is withdrawn from contact with the pulley 107. When this occurs, the cover 98 will return to the closed position under the pull of a spring 125 which is connected under tension between the cover and the shelf 35, or by a spring 125a connected under tension between pulley segment 102 and bracket member 51, or by action of both springs. Alternatively, the cover 98 may be arranged to be stopped in a position short of an upright position, and be thereby adapted to return to the closed position by gravity.

Drying mechanism

The drying mechanism D comprises simply a bank of infra-red lamps 126 which are arranged in an arcuate row with their centers directly behind the path of ball movement 31. The unit D' includes a fan 127 driven by an electric motor 128 for blowing air upwardly into an air duct 129 which terminates in a nozzle 130 directed for-

wardly. The nozzle 130 is preferably arcuate, extending along the path of ball movement 31. A partition wall 131 separates the upper dome portion of the housing into a compartment 132 in which the lamps 126 are positioned and a compartment 133 in which the air duct 129 is positioned. The heat radiated by the lamps 126 is partially retained in the compartment 132, thus tending to concentrate the heat. The blast of air from the nozzle 130 escapes from the housing through a vent 134 in the top of the housing, and thus the fumes from the drying paint are carried away so as to speed up the drying operation.

15 The infra-red lamps 126 and blower fan 127 are operated simultaneously as will be set forth more in detail hereinafter.

Discharge mechanism

20 The discharge unit E comprises a trough 135 which has an outlet communicating with the outlet 28. The bracket 74 may include a pair of upwardly extending arms 136 between which the trough 135 is secured as at 137. The entire 25 assembly of bracket 74, trough 71 and trough 135 may be supported by means of flanges 138 on the outer edges of the arms 136, and securing elements, such as rivets 139 securing the flanges 138 to the housing wall. The inner ends of the 30 side walls of the trough 135 are provided with outwardly turned cam flanges 140 which engage between the portions 63 of the spring fingers 61 of the ball carrying mechanism to spread the jaws 64 and release the ball 36 as the latter is dropped 35 opposite the inner end of the trough 135. The trough 135 has an upwardly curved finger 141 which engages beneath the ball and guides it into the trough.

Control circuit and operation

Referring now to Fig. 16, the main drive motor 42 forms part of a circuit from a source of power through a conductor 142, the coin controlled switch 43, a conductor 143, conductors 145 and 45 146, and a conductor 147. The conductors 142 and 147 may constitute a service cord to the machine from a conventional power outlet. The coin unit 25 will include some known mechanism 50 for opening the switch 43 and disposing of the coin after a predetermined length of time following the insertion of the coin (sufficient to permit the full cycle of operation of the machine) or the circuit just described may include a limit switch adapted to be momentarily actuated when 55 a cycle of operation of the machine has been completed, and in turn operate to open the circuit in any known manner.

It will now be apparent that the insertion of a coin will initiate one cycle of operation which will 60 terminate when the ball carrying arm 41 has been moved through a complete 360° range of movement. The initial and terminal position of the arm 41 is that shown in full lines in Fig. 7. It will be noted that in this position, the axis of 65 the arm is slightly above the center of the ball 36 resting in the pickup position. In this position, the spring arms 61 will be spread or partially spread. Upon energization of the circuit of the motor 42, the arm 41 will commence to move 70 downwardly as indicated by arrow 38, the fingers 61 will complete their spreading movement, causing the jaws 64 to move downwardly past the sides of the ball 36 until they reach the center of the ball, when they will be sprung inwardly by the 75 tension in the fingers 61 until their points engage

the opposite sides of the ball. Continuing downwardly, the jaws 64 will carry the ball with them, pushing the retractable ball support 77 downwardly and outwardly as previously described, and as shown in Fig. 11. When the ball has been moved beyond the retractable support 77, the latter will be pulled back by the spring 86 to its normal position for supporting another ball in the pickup position.

As the ball approaches the tank unit C, the solenoid 115 will be energized to effect the raising of the cover 98. The mechanism for effecting this includes a cam 151 on the shaft 37, a self-opening switch including a movable switch arm 152 engaged by the cam 151 and a contact 153 into engagement with which the arm 152 is moved by the cam 151, a conductor 154, the conductor 143, the switch 43, the conductors 142 and 147, the conductor 146, a conductor 155, the coil of the solenoid 115, and a conductor 156. The cam 151, the peripheral contour of which is shown in Fig. 4, includes a high portion 152 of sufficient circumferential extent to maintain the switch 152, 153 closed just long enough to allow the ball carrying mechanism to clear the cover 98 at each end of the tank unit C.

While the solenoid 115 remains energized, the drum 101 will be pressed against the pulley 107, receiving rotation therefrom to exert upon the cable 100 the necessary pull to raise the cover 98 and maintain it in the raised position. As soon as the solenoid is de-energized, the retractor spring 121 will withdraw the drum 101 from engagement with the pulley 107, and the cover 98 will then return to the closed position under the pull of the springs 125 and 125a, the drum 101 and shaft 104 simply rotating to permit the cable 100 to be drawn upwardly as the cover closes.

(Fig. 11 shows the position of the ball carrying mechanism in the mid point of its movement through the paint bath 97.)

Shortly after or simultaneously with the dropping of the cover 98, the infra-red lamps 126 and the blower motor 128 are simultaneously energized by mechanism including a cam 157 on the shaft 37, a self-opening switch including a switch arm 158 engaged by the cam 157 and a contact 159 against which the cam 157 is adapted to move the arm 158; the conductor 143, switch 43, conductors 142 and 147, conductors 146 and 161 in parallel, the lamps 126 and motor 128 in parallel, and conductors 162 and 163 in parallel. The cam 157, the peripheral contour of which is shown in Fig. 3, has a high portion 164 which is of the proper circumferential extent (approximately 180°) to maintain the lamps and blower energized throughout the movement of the ball carrying mechanism past the lamps and blower.

As the ball approaches the first of lamps 126, the star wheel 56 will engage the rack plate 58 and commence to rotate the rotatable portion of the ball carrying unit as indicated in the several dotted line positions in Fig. 13. The number of the openings 57 in the rack plate 58 is such that as the star wheel 56 disengages from the rack plate, the lugs 65 will enter the notches 66 and position the rotatable unit with the fingers 61 in the transverse plane as shown in full lines in Fig. 14, in order that the arms 61 may properly engage the cams 140 to release the ball into the discharge chute 135.

The agitator 95, 96 is operated continuously during the operation of the machine, to stir the paint in the bath 97, and prevent the formation of scum on the surface thereof. The motor 109

which drives the agitator is energized from a circuit parallel to the main drive motor circuit, said parallel circuit including the switch 43, conductors 142 and 147, a conductor 165, the motor 109, a conductor 166, and the conductor 143.

Modified form of invention

A number of the features of our invention may be embodied in a continuously operating ball painting machine for industrial use, such as that shown in Figs. 17 and 18. Fig. 17 is a schematic showing of such a machine, and therefore only the essential elements are shown. A hub 166 has a plurality of sockets 167 in which are mounted arms 61'. In each arm 61' is mounted a rotatable ball carrying unit including star wheel 56, stub shaft 52, and spring fingers 61, carrying jaws 64, all corresponding to the similarly numbered parts previously described. Balls 36 are fed down an inclined runway 71' onto a retractable ball support 77 from which they are picked up by the jaws 64, the latter being controlled by spreader cam flanges 83'. The fingers 61 leave the ends of the cams 83' at the proper point to bring the jaws 64 together upon the lowermost ball in the row of balls 36. The ball support 77 is yieldingly maintained in the ball supporting position shown in full lines by a spring 86' and a spring 86'', hooked together in series. As the support 77 is pushed downwardly by the ball, the spring 86' transmits movement to a lever 168 which is secured to a shaft 169 extending through the side walls of the runway 71'. Secured to the shaft 169 within the runway 71' is a stop-finger 170 which is drawn downwardly against the next to the last ball in the row of balls, to hold back the row of balls while the lowermost ball is being removed. The spring 86'' yields when the finger 170 is stopped against the ball that it engages. The spring 86'' is the retractor spring which draws both the support 77 and the finger 170 back to their normal positions when the support 77 is released.

The ball carrying units carry a series of balls 45 through the paint tank C' and past a battery of infra-red lamps 126 and a blower device 127, 128, 129, 130 similar to that previously described.

We claim:

1. In a ball coating machine, a tank for a coating bath, a cover for said tank, hinged thereto, a ball carrying means for moving a ball into and out of said tank, an agitator in said tank, a shaft extending through a wall of said tank for driving said agitator, means for raising said cover, including a draw cable and a drum around which said cable is yieldingly engaged, clutch means for establishing a drive between said agitator drive shaft and said drum, electrically operated means for engaging said clutch means, driving means for moving said ball carrying means, and control means driven by said driving means for automatically engaging said clutching means during the stage of movement of said ball carrying means in which said ball is moved into and out of said bath for transmitting, to said cable, cover raising movement.

2. In an automatic golf ball coating machine, a pair of opposed jaws for grasping a ball, a rotatable part carrying said jaws, means on which 70 said rotatable part is mounted for rotation on an axis at right angles to the common axis of said jaws, means supporting said mounting means for swinging movement such as to move said jaws in a circular orbit of which said axis of rotation is substantially a radius, a retractable support

for supporting a ball at a pick-up station near a starting point of said orbit, means disposed along a section of said orbit following said pick-up station for applying a coating to the ball, heating means disposed arcuately along said orbit beginning with a point substantially 180 degrees from said pick-up station and ending at a point substantially 90 degrees from said pick-up station, for heating the ball and drying said coating, means for slowly rotating said part as the ball is moved past said heating means whereby to spread the coating evenly on the ball, means for directing a stream of air against the ball for accelerating the drying action, and means immediately adjacent said pick-up station for spreading the jaws, releasing the ball, receiving the ball and conducting it to a discharge point.

3. A coating machine as defined in claim 2, wherein said orbit is arranged in a vertical plane, said coating means comprises a dipping tank occupying the lower section of the orbit, said pick-up station is located horizontally opposite the center of the orbit and said heating means commences diametrically opposite said pick-up station.

4. In an automatic golf ball recoating machine, a pair of opposed jaws for grasping the ball, a rotatable part carrying said jaws, a carrier on which said rotatable part is mounted for rotation, means supporting said mounting means for movement of said jaws in a circular orbit, a retractable support for supporting a ball at a pick-up station near a starting point of said orbit, means to spread said jaws as they approach said pick-up station and to release them for engagement with diametrically opposed points on the ball, means disposed at a coating station following said pick-up station for applying a liquid coating to the ball, heating means disposed along a section of said orbit following said coating station, means to slowly rotate the ball as it is carried past said heating means, said rotating means and heating means being arranged for continued operation until the coating has been dried to a non-fluid state and for terminating said slow rotation so as to leave the jaws fixed with relation to said carrier and means immediately adjacent said pick-up station for spreading said jaws to release the ball, for receiving the ball and for conducting the ball to a discharge point.

5. In an automatic golf ball recoating machine, a pair of opposed jaws for grasping a ball, a rotatable part carrying said jaws, a carrier on which said rotatable part is mounted for rotation, means supporting said mounting means for movement of said jaws in a circular orbit, a retractable support for supporting a ball at a pick-up station near a starting point of said orbit, means to spread said jaws as they approach said pick-up station and to release them for engagement with diametrically opposed points on the ball, means disposed at a coating station following said pick-up station for applying a liquid coating to the ball, heating means disposed along a section of said orbit following said coating station, means to slowly rotate the ball as it is carried past said heating means, said rotating means and heating means being arranged to become operative on the ball immediately at the end of the coating operation, to continue in operation until the coating has been dried to a non-fluid state, and to terminate said slow rotation so as to leave the jaws fixed with relation to the carrier, means to circulate air over the ball during the operation of said heating means to

accelerate the drying of the coating, and discharge means immediately adjacent said pick-up station and at the end of said orbit, for spreading said jaws, releasing and receiving the ball, and conducting it to a discharge point, said heating and air circulating means being effective substantially throughout the period of movement of the ball from the coating station to said discharge means.

10 6. In a ball coating machine, a plurality of ball carrying means movable in a circular path in a vertical plane, a coating tank disposed to receive a ball at a point near the bottom of said path, a retractable support for positioning a ball at a pickup point at a side extremity of said path above said tank, means yieldingly maintaining said support normally in a position to support a ball, said ball carrying means including jaw means including a pair of opposed needle points adapted to engage the ball at horizontally and diametrically opposite points and to carry it downwardly, forcing said support to retract out of the path of said downward movement, means for spreading said jaw means just prior to its coming opposite the ball and for then releasing said jaw means for engagement of the ball, means for moving said ball carrying means in said circular path, a downwardly inclined trough for supporting a column of balls in position to enter upon said retractable support, and means actuated by the retractable support to yieldingly engage said column of balls to restrain movement thereof toward said retractable support while the latter is being retracted.

15 7. In a ball coating machine, ball carrying means movable in a circular path in a vertical plane, a coating tank disposed to receive the ball at a point near the bottom of said path, a retractable support for positioning a ball at a pickup point at a side extremity of said path above said tank, means yieldingly maintaining said support normally in a position to support a ball, said ball carrying means including a pair of opposed needle points adapted to engage the ball at horizontally and diametrically opposite points and to carry it downwardly, forcing said support to retract out of the path of said downward movement, means for spreading said jaw means just prior to its coming opposite the ball and for then releasing said jaw means for engagement of the ball, means for moving said ball carrying means in said circular path, a discharge chute disposed immediately above said retractable support and means for spreading said jaw means when the ball reaches a position opposite the receiving end of said chute, to deliver the ball into said discharge chute, said discharge chute being inclined downwardly and outwardly, to carry the ball out of the machine, and a housing for the machine, having an inlet communicating with said retractable support and an outlet communicating with said discharge chute, said inlet and outlet being disposed adjacent each other.

20 8. Coin controlled ball coating apparatus including a ball inlet, means communicating with said inlet for supporting a ball in a pickup position, ball carrying means movable in a predetermined path past said supporting means, said carrying means including ball gripping means and means to actuate said gripping means as it approaches the ball supporting means so as to cause the same to straddle and then grip the ball, means to coat the ball at a subsequent stage of movement along said path, means to dry the

ball at a further stage of movement along said path, control means actuated by said ball carrying means for energizing said ball drying means during the stage of ball drying movement, a discharge outlet at a final point along said path, means to release the ball from said gripping means for discharge into said outlet, electric motor drive means for moving said ball carrying means throughout said successive stages of movement, and a coin operated switch for completing a circuit to said motor for one complete cycle of operation.

9. Coin controlled ball coating apparatus including a ball inlet; means communicating with said inlet for supporting a ball in a pickup position; ball carrying means movable in a predetermined path past said supporting means, said carrying means including ball gripping means and means to actuate said gripping means as it approaches the ball supporting means so as to cause the same to straddle and then grip the ball; means to coat the ball at a subsequent stage of movement along said path; means to dry the ball at a further stage of movement along said path; said ball coating means comprising a tank for a coating bath, and a cover for said tank, electrically controlled means for raising said cover during the stage of movement of the ball through said bath, control means actuated by said ball carrying means for initiating and terminating the operation of said cover lifting means during said stage of movement; control means actuated by said ball carrying means for subsequently energizing said drying means during the stage of movement of the ball past said drying means; means to release the ball from said gripping means for discharge into said outlet; electric motor drive means for moving said ball carrying means throughout said successive stages of movement; and a coin operated switch for completing a circuit to said motor for one complete cycle of operation.

10. In an automatic golf ball coating machine, a pair of opposed jaws for grasping a ball; a rotatable part carrying said jaws; an arm on the outer end of which said part is journalled for rotation on an axis at right angles to the common axis of said jaws; means supporting the inner end of said arm for swinging movement such as to move said jaws in a circular orbit; a retractable support for supporting a ball at a pick-up station on said orbit near a starting point in the orbital movement of said jaws;

means to spread said jaws as they approach said pick-up station and to release them for engagement with diametrically opposed points on the ball; means to apply a coating to the ball at a station on said orbit following said pick-up station; means to slowly rotate the ball along a section of said orbit following the coating operation, said rotating means comprising a drive element attached to said rotatable part and a drive member disposed arcuately along the last mentioned section of said orbit, the rotatable connection between said part and said arm being such as to provide for free rotation of said part solely in response to the coaction between said drive element and drive member, whereby the rotation of said part will terminate when the drive element and drive member become disengaged, the terminal end of said drive member being so located that disengagement will occur when said jaws are in a plane normal to the plane of said orbit, self-centering interacting latching means on said rotatable part and said arm respectively; resilient means for yieldingly urging said latching means into interengagement such as to accurately locate said jaws in said normal plane when said jaws are not being rotated, said resilient means yielding to allow said latching means to disengage so as to permit the rotation of said rotatable part; and means immediately adjacent to said pick-up station for spreading said jaws apart to release the ball, for receiving said ball and for conducting the ball to a discharge point.
